(57) **CLAIM**

The ornamental design for a cup holder, as shown and described.

DESCRIPTION

FIG. 1 is a top, front, right perspective view of a cup holder showing my new design;

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof; and,

FIG. 8 is bottom, rear, left perspective view thereof.

The uneven-length broken lines represent unclaimed boundaries of the claimed design. The even-length broken lines showing the remainder of the cup holder represent unclaimed subject matter and form no part of the claimed design.

1 Claim, 5 Drawing Sheets(56)
